Attorney¹

UNITED STATES PATENT OFFICE.

JACOB W. WADDELL, OF COLUMBUS, OHIO.

IRONING-BOARD CABINET.

Application filed November 11, 1927. Serial No. 232,682.

This invention relates to improvements in ironing board cabinets and, more narrowly, to cabinets of the type adapted to be built into the wall of a room and provided with extensible or foldable supporting members which when extended will lie perpendicularly to the cabinet proper for use in supporting garments or fabrics during ironing operations and which when collapsed will be compactly arranged within the cabinet so as to be out of the way and yet readily accessible when needed.

It is a primary object of the invention to provide an ironing table structure of this character which will be of simple, durable and substantial construction and which may be conveniently operated to assume collapsed or extended positions without difficulty or mechanical complications.

Other objects of the invention will be in part obvious and in part pointed out hereinafter.

For a further understanding of the invention reference is to be had to the following description and the accompanying drawing, wherein:

Figure 1 is a vertical sectional view taken through the improved ironing table structure comprising the present invention,

Figure 2 is a front elevation of the structure when in its folded position,

Figure 3 is a vertical sectional view taken on the line indicated at 3—3 of Figure 2,

Figure 4 is a transverse sectional view on the line 4—4 of Figure 1.

Referring more particularly to the drawing the numeral 1 designates the cabinet of the ironing table structure comprising the present invention. This cabinet is preferably placed within a recess 2 provided in a wall 3 of a room in which the ironing board is used. The cabinet is formed to include a back wall 4, side, top and bottom walls 5, a rectangular molding frame 6 and a hinged door 7 at the front thereof.

The folding ironing table structure which is adapted to occupy said cabinet, comprises a fixed transversely extending bar or stop 8 secured to the back wall 4 of the cabinet and arranged about midway of the height of the cabinet, the bar acting in the capacity of a stop for the principal board 9 of the structure.

The board 9 when in active use extends perpendicularly to the casing as shown in Figure

1 and its inner edge engages the under side of the stop 8 so as to limit the outward swinging movement of said board. Intermediate the length of the board 9 and connected with the lower surface thereof is a hinge 10, which latter is connected with a supporting frame 11, consisting of upwardly converging bars rigidly secured in spaced relationship. The lower end of the frame 11 is hinged as at 12 to the bottom of the cabinet 1. Connected with the sides of the cabinet for pivotal movement are links 13, which have their lower ends provided with elongated slots 14 for the reception of pins 15 provided on the frame 11, the links 13 being employed for the purpose of stabilizing the construction and to limit the outward swinging movement of the frame 11.

Hinged to the inner end of the board 9 as at 16 is a locking strut 17, which in this instance comprises an outwardly extending member connected at its outer end by means of a transversely extending bar 19. This bar is adapted to engage with stationary wedges 20 provided on the sides of the frame 11 and it will be seen that when the board 9 is swung to assume a horizontal position with its inner end in engagement with the stop 8, the strut 17 is forced downwardly so that the crossbar 19 may be forced firmly into frictional engagement with the inclined surfaces of the wedges 20, thus frictionally locking the ironing table structure in its extended position.

To release the board structure and to permit the latter to be folded the strut 17 is moved upwardly so as to free the bar 19 from engagement with the wedges 20. This permits the board 9 to swing about its hinged connection 10 with the frame 11, and the entire construction is then folded inwardly by being oscillated about the hinged connection between the lower part of the frame 11 and the bottom of the casing. This permits the part to assume the position disclosed in Figure 3, where it will be observed that the ironing table structure per se is compactly arranged within the casing, permitting the latter to be of rather shallow depth. If desired, a sleeve board 21 may be hinged as at 22 upon the stop 8 so that the sleeve board may assume the position disclosed in Figure 1, wherein the sleeve board is located in parallelism with the main board and in superposed relation with respect thereto. The bottom of the sleeve board is provided with a stop bar 23, which engages

with the upper surface of the board 9 when the latter is extended and serves to properly space the sleeve board from the main board.

While I have described what I consider to be the preferred form of the present invention yet it will be understood that various changes and departures from such specific form may be made without departing from the spirit and principles of the invention as set forth in the following claims.

What is claimed is:

1. A foldable ironing table structure comprising a cabinet, a board, a supporting frame hinged at one end to said board intermediate of the length of the latter, the other end of said frame being hinged to the bottom of said cabinet, means to limit the outward movement of said frame, a stop member carried by said cabinet and engageable with the inner end of said board to limit the outward swinging movement thereof, and a locking strut hinged at one end to the inner end of said board and having its other end adapted to frictionally engage with the intermediate portion of said frame to maintain said board in its extended horizontal position.

2. In an ironing table structure of the character described, a cabinet, a board, a bracing frame having its lower end hinged to the bottom of said cabinet, the upper end of said frame being hinged to an intermediate

portion of said board, said frame having the intermediate portion thereof provided with parts having inclined surfaces, a stop member carried by said cabinet and engageable with the inner end of said board to limit the outward swinging movement thereof, a locking member hinged to the inner end of said board and having its outer end adapted to frictionally engage with the inclined surfaces of said frame and means to limit the outward movement of said frame.

3. In a foldable ironing table structure, a cabinet, a board, a bracing frame for said board having its lower end hinged to the bottom of said cabinet, the upper end of said frame being hinged to said board intermediate of the length of the latter, stationary wedges provided upon said frame at positions intermediate the length thereof, a locking member hinged at one end to the inner end of said board and having the other end thereof adapted to frictionally engage with said wedges, a stop member carried by said cabinet and engageable with the inner end of said board to limit the outward swinging movement thereof, and a pair of links pivotally connected with said cabinet and having the outer ends thereof provided with slots for the reception of pins carried by said frame.

In testimony whereof I affix my signature.

JACOB W. WADDELL.
